UNITED STATES PATENT OFFICE.

JAMES B. MELLOR, OF BALTIMORE, MARYLAND.

CHURN-DASHER.

SPECIFICATION forming part of Letters Patent No. 349,854, dated September 28, 1886.

Application filed June 15, 1886. Serial No. 205,261. (No model.)

To all whom it may concern:

Be it known that I, JAMES B. MELLOR, a citizen of the United States, residing at Baltimore, in the State of Maryland, have invented 5 certain new and useful Improvements in Churn-Dashers, of which the following is a specification.

My invention relates to an improved churn-dasher; and it consists of an improvement on 10 the dasher for which Letters Patent of the United States, numbered 110,487, were granted me December, 1870.

In the accompanying drawings, Figure 1 is 15 a side view of the dasher and a sectional view of the churn-barrel. Figs. 2 and 3 are different side views of the dasher.

The letter A designates the barrel of a churn; B, the shaft, which is fixed in bearings *c d* in the heads of the churn, and has outside of 20 one head a projecting end, B', to which may be attached a crank or other means for turning it.

In the present instance the churn is shown 25 standing on one head upright. Two arms, *e*, are attached to the shaft at one end, and each upon an opposite side from the other, and both of said arms incline upward from their attached ends. When the barrel A is standing on one end, as shown, and the shaft B is 30 revolved, the movement of the two upward-inclined arms *e* will give to a large part of the cream an upward motion. To that position of the cream, however, which lies on the bottom head of the churn this "upward motion" is 35 not imparted. Two additional arms, *f*, have position and extend parallel with the shaft B, and point straight downward, and are provided with holes *g*. These parallel arms are each fixed to the lower end of a downward-inclined arm, *h*, whose upper end is attached to 40 the shaft B at or near the other end. The

downward-projecting arms *f h* project from sides of the shaft different from the upward-inclined arms *e*, and, considered with reference to the shaft-axis, these arms *f h* project 45 at right angles with respect to the arms *e*. Thus each downward-pointing arm embraces an upper portion, *h*, which inclines, and a lower portion, *f*, which is parallel with the shaft. The movement of these arms *f h* produces not 50 only a downward motion of the cream, but the lower parallel portion, *f*, having its lower end free or unattached, most effectually breaks up the counter-currents and agitates and breaks 55 up the cream on the bottom head which is undisturbed by the upward-inclined arms. A dasher thus constructed is found in practice to be very rapid in its action on the cream, and very much superior to the dasher shown 60 in my former patent above referred to.

Having described my invention, I claim and desire to secure by Letters Patent of the United States—

A churn comprising the barrel A and revolvable shaft B, having at one end two upward-inclined arms, *e*, each attached at an opposite side, and at or near the other end two downward-pointing arms projecting from a different side of the shaft and at right angles with respect to the first-named arms, each of said 65 downward-pointing arms consisting of an upper portion, *h*, which inclines downward, and a lower portion, *f*, which is parallel with the revolvable shaft and has its lower end free or unattached, as shown and described. 70

In testimony whereof I affix my signature in the presence of two witnesses.

JAMES B. MELLOR.
